CLAIM

The ornamental design for a golf cart fairing, as shown and described.

DESCRIPTION

FIG. 1 is a front perspective view of the golf cart fairing, showing the new design;

FIG. 2 is a left rear perspective view of the golf cart fairing thereof;

FIG. 3 is a right rear perspective view of the golf cart fairing thereof;

FIG. 4 is a front elevational view of the golf cart fairing thereof;

FIG. 5 is a rear elevational view of the golf cart fairing thereof;

FIG. 6 is a left side elevational view of the golf cart fairing thereof;

FIG. 7 is a right side elevational view of the golf cart fairing thereof;

FIG. 8 is a top plan view of the golf cart fairing thereof; and, FIG. 9 is bottom plan view of the golf cart fairing thereof. The broken lines in the drawings illustrate environmental subject matter and form no part of the claimed design.

1 Claim, 9 Drawing Sheets
